UNITED STATES PATENT OFFICE.

PER TORSTEN BERG, OF MUNHALL, PENNSYLVANIA.

TIPPING METALLURGICAL FURNACE.

SPECIFICATION forming part of Letters Patent No. 617,918, dated January 17, 1899.

Application filed October 29, 1897. Serial No. 656,793. (No model.)

To all whom it may concern:

- Be it known that I, PER TORSTEN BERG, of Munhall, in the county of Allegheny and State of Pennsylvania, have invented a new and useful Improvement in Tipping Metallurgical Furnaces, of which the following is a full, clear, and exact description, reference being had to the accompanying drawings, forming part of this specification, in which—
- 10 Figure 1 shows in side elevation a metallurgical furnace constructed in accordance with my invention, half of the same being in vertical central section. Fig. 2 is an end elevation of the furnace. Fig. 3 is a detail view showing the water-cooled facing at the end of the revolving flue-passage of the vessel and is in vertical section on the line III III of Fig. 4. Fig. 4 is a bottom plan view of the part shown in Fig. 3.
- 15 The furnace shown in the drawings is designed to receive molten metal and subject the same to heat. The construction which I illustrate may be used either for open-hearth furnaces proper or for metal mixers or other vessels in which metal is contained and heated.

- The vessel or furnace is a tilting vessel mounted on supports or trunnions on which it can be turned and having connections at 20 the ends with flues for admitting gas or heated air or gas and air. In the construction shown in the drawings the vessel is connected with flues leading from regenerators for the heating of the air used in combustion. The gas 25 is admitted without passing through such flues; but modifications by which the connection may be made with both air and gas flues will readily suggest themselves.

- The special point of construction to which 30 my invention relates is the means for connecting the furnace to the flues; and it consists in providing the furnace at the ends with flue-passages which extend in line with the axis of rotation of the vessel and are formed 35 at the ends substantially in the arc of a circle registering with a corresponding arc at the ends of the stationary flues, so that the rotation of the vessel will not disturb the connection.

- 40 In the drawings, 2 represents the vessel or furnace, having, as shown, a strong outer metallic frame or shell and an inner refractory

lining and having circular shoes 3, supported on rollers 4 and enabling it to be tilted laterally by a cylinder 5 or other suitable motor. At the ends of the vessel are openings 55 6 6 for admission of heated air to the furnace-hearth. These openings communicate with vertically-extending passages 7, formed at the ends of the furnace and having their 60 lower ends 8 formed on a circular arc. These ends 8 are adjacent and are counterparts of the upper ends of flues 9, leading from regenerators 10, and the upper ends of the latter flues are, as above suggested, formed on 65 arcs conforming to the ends of the passages 7. The construction is therefore such that when the furnace is rotated the passages 7 will also register with the flues 9, and the space between them which is allowed for play 70 of the parts may, if desired, be easily sealed by interposing some loose bricks or sand. The passage 7 is wider than the mouth of flue 9, as shown by dotted lines in Fig. 2, so that these parts will always be in register and there 75 will always be an opening of full area from the flue. This construction is very convenient, as it affords a simple and effective flue connection which is not disturbed by expansion or contraction or warping of the parts, 80 as in like furnaces heretofore known.

In order to render the apparatus more durable, I prefer to face the lower ends of the passages 7 with metal shoes 11, (shown particularly in Figs. 3 and 4,) which have hollow 85 frames and are provided with a water-cooling passage 12. To supply water to the passage 12, I employ jointed swinging pipes 13, or other flexible connections may be used for such purpose. The gas for combustion may be admitted through an opening 14 and is supplied 90 thereto by a swinging pipe 15.

I claim—

1. A tilting metallurgical furnace or vessel arranged to be rotated on a horizontal axis 95 passing through its ends, and having an end opening through which the axis passes, and a flue extending from the said opening in line with the axis, and provided with a depending end, and a stationary flue having its end arranged to register with the furnace-flue; substantially as described.

2. A tilting metallurgical furnace or vessel arranged to be rotated on a horizontal axis and

having a flue extending in line with the axis of rotation, said flue having a depending portion with a curved lower end and a stationary flue having a correspondingly-curved upper end arranged to register with the furnace-flue; substantially as described.

3. A tilting metallurgical furnace or vessel arranged to be tipped on a horizontal axis, and having a flue with an end portion extending across the axis of rotation and formed with a curved end having a water-cooled shoe, and a stationary flue having a correspondingly-curved end arranged to register with the furnace-flue; substantially as described.

15 4. A tilting metallurgical furnace or vessel having end openings with downwardly-extending flues having curved ends and stationary flues having curved upper ends arranged to register with the furnace-flues; substantially as described.

20 5. A tilting metallurgical furnace or vessel arranged to swing on a horizontal axis, and having a flue extending in line with the axis of rotation and provided with a lateral extension having a curved end, and a stationary flue having a correspondingly-curved end, ar-

ranged to register with the furnace-flue, the mouth of one of these flues being wider than the other; substantially as described.

25 6. A tilting metallurgical furnace or vessel arranged to be rotated on a horizontal axis and having a depending flue, a stationary flue having its upper end arranged to register with the furnace-flue, and an interposed sealing of loose material; substantially as described.

30 7. A tilting metallurgical furnace having a flue-opening through which the axis of rotation passes and a flue extending from the opening in line with and then across the axis of rotation, and a stationary flue across the mouth of which the furnace-flue swings, the 35 hearth of the vessel being in position for refining or operating upon the metal, when the flues are in registry, substantially as described.

40 45 In testimony whereof I have hereunto set my hand.

PER TORSTEN BERG.
